UNITED STATES PATENT OFFICE.

LESTER E. SAMUEL, OF BROWNSVILLE, OREGON.

CIRCUIT-BREAKER FOR REVERSIBLE MOTORS.

1,399,801.

Specification of Letters Patent. Patented Dec. 13, 1921.

Application filed April 17, 1920. Serial No. 374,716.

To all whom it may concern:

Be it known that I, LESTER E. SAMUEL, a citizen of the United States, residing at Brownsburg, in the county of Linn and 5 State of Oregon, have invented a new and useful Circuit-Breaker for Reversible Motors, of which the following is a specification.

My invention relates to improvements in 10 circuit breakers for reversible motors, in which a manually operated switch starts the rotation of a motor in either direction, while the stopping, after a certain number of revolutions, is accomplished automatically.

15 The objects of my invention are to produce an apparatus, which will operate window shades, window sashes, fire doors, revolving shutters, etc., from a distance.

I attain these objects with the mechanism 20 illustrated in the accompanying drawing in which—

Figure I is a plan of the essential elements with the complete wiring diagram.

Fig. II is a section through Fig. I along 25 the line *a—a* showing in side elevation the circuit breaker which stops the motor automatically.

Similar numerals refer to similar parts throughout the several views.

30 The electric current, issuing from the wire 1 of the main circuit proceeds as follows: wire 2, blade 3 of the knife switch 4, wire 5, to the motor 6, setting the latter in rotation, issuing from there through the wire 7, into the blade 8 of the knife switch, through the wire 9, into the roller shaft 10, and the roller 11. The latter being in metallic contact with the circuit breaker 12, the current proceeds through the circuit breaker 35 40 45 50

opposite direction (indicated in dotted lines) will establish the following circuit: Wire 1, wire 19, blade 3^a, wire 19^a, motor 6, causing rotation in opposite direction, wire 20, blade 55 8^a, wire 21, shaft 22, roller 23, (see Fig. II) circuit breaker 12, shaft 13, and finally through wire 14 back into the main circuit 15. Rotation of the circuit breaker will proceed until roller 23 lands on the 60 insulating strip and stops rotation of the motor. Roller 11 being brought again in metallic contact with the circuit breaker permits then also passage of electric currents when the switch is thrown into the 65 position first described.

Thus the motor, after having performed a certain number of revolutions stops automatically. The ends of the roller shafts 10 and 22, where the rollers 11 and 23 are attached, should possess some flexibility.

The tension springs 24 insure positively contact of the rollers 11 and 23 with the rim of the circuit breaker 12.

The device which needs winding and unwinding may be attached in any suitable manner either to the shaft of the motor 6 or to any of the shafts 13, 16 or 17.

I claim:

In a circuit breaker, the combination of a 80 rotary circuit breaking wheel having a strip of insulating material across its periphery, two contact wheels traveling on said periphery, flexible shafts supporting the contact wheels, tension springs attached to the 85 flexible shafts to press the contact wheels against the periphery of the circuit breaking wheel, a reversible motor, a train of gears between the motor and the circuit breaking wheel, two electric circuits for operating the motor in either direction, each circuit having a separate contact wheel but having the circuit breaking wheel in common, a manually operated switch to send an electric current through either one of the 90 95 circuits, said current being automatically interrupted when one of the contact wheels arrives on the insulating strip of the circuit breaking wheel.

Signed by me at Portland, Oregon, this 100 12th day of April, 1920.

LESTER E. SAMUEL.

Throwing now the knife switch 4 in the
